[57] CLAIM

The ornamental design for a combined nestable bath toy, as shown and described.

DESCRIPTION

FIG. 1 is a front perspective view of a combined nestable bath toy showing my new design;

FIG. 2 is a front perspective view thereof in an exploded condition;

FIG. 3 is a rear elevational view of the bottom element shown in FIG. 2 shown in an inverted condition;

FIG. 4 is a top plan view thereof;

FIG. 5 is a side elevational view thereof;

FIG. 6 is a bottom plan view thereof;

FIG. 7 is a front elevational view thereof in an inverted condition;

FIG. 8 is a rear elevational view of the center element shown in FIG. 2 shown in an inverted condition;

FIG. 9 is a top plan view thereof;

FIG. 10 is a side elevational view thereof;

FIG. 11 is a bottom plan view thereof;

FIG. 12 is a front elevational view thereof in an inverted condition;

FIG. 13 is a rear elevational view of the top element shown in FIG. 2 shown in an inverted condition;

FIG. 14 is a top plan view thereof;

FIG. 15 is a side elevational view thereof;

FIG. 16 is a bottom plan view thereof; and

FIG. 17 is a front elevational view thereof in an inverted condition.
